UNITED STATES PATENT OFFICE.

ALFRED B. GUNTHEL, OF SEA CLIFF, NEW YORK.

DESIGN FOR A GOBLET OR SIMILAR ARTICLE.

42,999.

Specification for Design.

Patented Sept. 10, 1912.

Application filed June 20, 1912. Serial No. 704,887. Term of patent 7 years.

To all whom it may concern:

Be it known that I, ALFRED B. GUNTHEL, a citizen of the United States, residing at Sea Cliff, in the county of Nassau and State of New York, have invented a new, original, and ornamental Design for a Goblet or Similar Article, of which the following is a specification, reference being had to the accompanying drawing, forming a part thereof.

The figure is a view in elevation of a goblet or similar article, showing my new design.

I claim:

The ornamental design for a goblet or similar article, as shown.

ALFRED B. GUNTHEL.

Witnesses:

JOHN V. STORCK,
HUGO MOCK.
